ARTICLE HOLDER

William H. Inman, Newark, N. Y., assignor to
 Bloomer Bros. Company, Newark, N. Y., a corporation of New York

Application July 5, 1932, Serial No. 620,757
 Renewed May 17, 1933

18 Claims. (Cl. 229—29)

This invention relates to article holders, and more particularly to those made of sheet material and arranged to resiliently support and cushion fragile articles such, for example, as 5 eggs. One object of the invention is the provision of a holder of this class which not only effectively cushions and supports the eggs, but which is simple in construction and inexpensive to manufacture.

10 Another object is the provision of a holder of this kind adapted to be used as a one-piece cushioning filler arranged to be removably positioned within an outer enclosing box, or, with slight alterations, as a complete one-piece container in which the eggs are enclosed and 15 resiliently supported.

A further object is the provision of such a 20 filler which when removed from the enclosing box constitutes a tray-like member adapted by itself to retain and resiliently cushion the eggs or other articles positioned therein.

A still further object is the provision of such a 25 holder which may be easily and quickly erected to provide a plurality of cushioned article receiving compartments, or may be collapsed substantially into a plane for storing or shipping.

An additional object is the provision of a holder 30 constructed so as to expose a large part of the contained articles to permit ready inspection thereof.

To these and other ends the invention resides in certain improvements and combinations of parts, all as will be hereinafter more fully described, the novel features being pointed out in 35 the claims at the end of the specification.

In the drawings:

Fig. 1 is a perspective view of a one-piece filler or tray constructed in accordance with the present invention;

40 Fig. 2 is a top plan view of the filler in the collapsed or folded position;

Fig. 3 is a vertical sectional view taken substantially on the line 3—3 of Fig. 2;

45 Fig. 4 is a plan view of the sheet from which the filler is formed;

Fig. 5 is an end view of the box in which the filler is adapted to be removably positioned;

Fig. 6 is a front view of the box illustrated in 50 Fig. 5;

Fig. 7 is a bottom view of the box illustrated in Fig. 5 in the folded or collapsed condition;

Fig. 8 is an end view of the collapsed box shown in Fig. 7;

55 Fig. 9 is a vertical sectional view taken trans-

versely of the box showing the relation of the filler thereto;

Fig. 10 is a front elevation view of the box and 5 filler illustrated in Fig. 9 with the front of the box cut away so as to show more clearly the arrangement of the various parts of the filler;

Fig. 11 is a plan view of the box and filler with the cover in open position and partly broken away;

Fig. 12 is a front elevation view of a modified 10 construction arranged to form a one-piece container;

Fig. 13 is a view similar to Fig. 12 with the front wall cut away to show more clearly the 15 construction of the parts comprising the container.

Fig. 14 is a plan view of the container illustrated in Figs. 12 and 13 with the cover in open position and partly broken away;

Fig. 15 is a vertical sectional view taken trans- 20 versely through two adjoining containers of the type illustrated in Figs. 12, 13, and 14 showing the line contact formed between the two containers;

Fig. 16 is a bottom view of the container il- 25 lustrated in Figs. 12, 13, and 14 in the collapsed or folded condition;

Fig. 17 is a vertical sectional view taken sub- 30 stantially on the line 17—17 of Fig. 16;

Fig. 18 is a plan view of the blank from which the container is formed;

Fig. 19 shows still another modification in which the one-piece filler is formed to provide three rows of cells;

Fig. 20 shows a modified form of one-piece con- 35 tainer similar to that illustrated in Fig. 15 but formed with three rows of cells;

Fig. 21 is a plan view of the filler illustrated in Fig. 19 when removed from the box and collapsed;

Fig. 22 is a vertical sectional view taken sub- 40 stantially on the line 22—22 of Fig. 21; and

Fig. 23 is a fragmentary vertical sectional view taken substantially on the center line of the container or filler showing means for locking the 45 center partition portion and the transverse partition members in interengaging relation.

The same reference numerals throughout the several views indicate the same parts.

This invention is embodied in the present instance, by way of illustration, in an article holder adapted to resiliently support and cushion fragile articles such, for example, as eggs. The holder is made from a single piece of cardboard, or other analogous substance, suitably cut, scored 50 and

and folded to form V-shaped bottom portions adapted to resiliently support and cushion the eggs, a central longitudinal partition portion intermediate the bottom portions and extending 5 upwardly therefrom, and a transverse wall from which transverse partition members are swung upwardly to cooperate with the longitudinal portion to maintain the bottom portions in erected position and to provide a plurality of article receiving compartments. The blank may be thus formed to provide a one-piece filler and egg holder adapted to be removably positioned within an enclosing container, or, with modifications, as a combined one-piece filler and container. The 10 filler is adapted to effectively support and cushion the eggs independently of the enclosing box or body portion.

Referring now to Fig. 1 of the drawings, there is shown what is known in the trade as a 2 x 6 filler formed from a single strip of cardboard scored along the parallel lines 36, 37, and 38 to divide the strip into four main sections, Fig. 4, designated by the numerals 40, 41, 42, and 43. Each of the sections 40 and 42 is provided with an 15 intermediate score line 50 which divides the section into members 51 and 52 which when folded on the score line 50 are arranged to form a V-shaped bottom portion, as illustrated in Figs. 1 and 9. The V-shaped bottom portions are separated by means of an upstanding partition portion 55 which extends upwardly from the bottom portions and is formed by folding the section 41 of the strip upon itself by reason of the score line 56. The partition portion extends the full 20 length of the filler and provides a central longitudinal partition member which divides the container into two rows of cells, each of which is provided with a cushioning bottom and is adapted to receive six eggs or other fragile articles.

The section 43 of the strip is hingedly secured 25 to the outer edge of one of the inclined bottom members 51, as shown in Fig. 4, and may be folded on the score line 38 so as to extend transversely of the container in a substantially horizontal plane. The free edge of the section 43 is provided with an integral securing flap 60 hingedly secured thereto along the score line 61. The flap 60 may be adhesively or otherwise attached to the opposite inclined bottom member 51 to secure the section 43 thereto, as clearly illustrated 30 in Figs. 1 and 9.

A plurality of partially severed tongues 65 are formed from the section 43 by means of a plurality of transverse slits 66, spaced longitudinal slits 67 extending along the score lines 38 and 61, and diagonal slits 68 connecting the slits 66 and 67. The slits 66, 67, and 68 are arranged so as to leave small triangular shaped tabs 71 which connect the tongues 65 to opposite sides 35 of the bottom, as shown in Fig. 1. These tabs are scored at 72, in alinement with the slits 66, to enable the tongues 65 to be swung upwardly out of the plane of the attaching tabs 71 and into spaced vertical planes to provide transverse partition members which extend across the container and divide the rows of cells formed by the partition portion 55 into six separate compartments, each adapted to receive a single article 40 such, for example, as an egg. When the tongues 65 are thus swung up or erected, the lower edges 75 thereof extend across and bridge the tops of the V-shaped bottom portions and are secured thereto at the lower corners thereof. The upper edges 76 thereof preferably lie in the horizontal

plane of the top of the partition portion, as shown in Figs. 1 and 9.

Each of the transverse partition members or tongues 65 is formed with a slot 80 extending upwardly a short distance from the lower edge 75 thereof and adapted to receive the lower part 5 of the partition portion 55. The upper or unslotted portions of these transverse members are disposed in registering slots 81 which extend downwardly from the upper edge of the portion 10 55 substantially in the planes of the erected transverse members. The bottoms of the slots 81 terminate substantially in the plane of the bottoms of the slots 80. These slots 80 and 81 thus afford means for assembling and securing 15 the longitudinal and transverse partition members in proper interengaging relation to form a plurality of article receiving compartments. The upper ends 82 of the slots 81 are preferably enlarged or flared out to facilitate the insertion of 20 the unslotted portion of the transverse members.

The longitudinal portion 55 is preferably 25 locked to and supported by the transverse partition members 65 so as to maintain the bottom members 50 and 51 in inclined relation. This locking means comprises, in the present embodiment, a plurality of lugs 83, of the shape best shown in Fig. 23, which extend across and partly close the upper ends of the slots 81. These lugs are arranged to extend through registering apertures 84 in the complementary transverse members 65 to lock the longitudinal portion thereto, in the manner clearly illustrated in 30 Fig. 23.

By means of this arrangement, the bottom 35 portions 51 and 52 are firmly held in V-shape by the connection with the outer ends thereof of the adjacent cross wall or section 43, and by reason of the interlocking engagement of the longitudinal portion 55 with the transverse members 40 65. The transverse members thus not only provide means for holding the longitudinal portion against lateral movement and for dividing the rows of cells into article receiving compartments, but also afford supporting means for the longitudinal portion and the bottom portions and thus secure the latter inclined against a very substantial degree of pressure so as to maintain 45 effective cushioning supports for the eggs.

When the filler, with its contained eggs, is 50 stored or shipped, it is positioned within an outer enclosing box or body portion made from a single piece of cardboard having a bottom 95, ends 96, back 97, front 98, and a cover 99 with a closing flap 100. The flap 100 preferably extends the full height of the body portion and rests on the bottom 95, see Fig. 9, to afford a support for the cover 99. The filler is preferably so constructed that when positioned within the box, the transverse members 65 and the longitudinal portion 55 extend to the top of the body portion and engage the under side of the cover 99 to assist the flap 100 to support the cover and to prevent it being pushed down and crushing 55 the eggs.

The above described one-piece filler thus not only divides the interior of the box or body portion into a plurality of article receiving compartments, but also affords resilient bottoms therefor which effectively cushion and support the articles. This filler also provides a tray-like member adapted to be used independently of the body portion, and, when so used, provides an adequate support and cushion for the eggs. This tray-like member, when removed from the box, 60 65 70 75 80 85 90 95 98 99 100 105 110 115 120 125 130 135 140 145 150 155 160 165 170 175 180 185 190 195 200 205 210 215 220 225 230 235 240 245 exposes a large portion of the eggs and is thus admirably adapted for use as a display carton by wholesale and retail merchants. The consumer may also use this filler as a separate container for storing the eggs in a refrigerator or other suitable storage place. When the filler is used as a separate supporting and cushioning container, it not only provides adequate ventilation for the eggs and thus prolongs the time they will remain fresh, but also facilitates the removal of individual eggs therefrom.

The body portions and fillers are separately bundled and shipped from the carton manufacturer to the egg packer in a collapsed or knocked down condition. The box or body portion may be readily collapsed substantially into a plane by reason of the diagonal score lines 101 and 102 arranged on the ends and front wall respectively, as clearly illustrated in Figs. 5 and 6. The filler is collapsed by disengaging the lugs 83 from the apertures 84 and flattening the longitudinal portion 55 into the plane of the adjacent bottom members 52. The outer bottom members 51 are then bent on the score lines 50, and, with the collapsed tongues 65, overlie the portion 55 and the bottom members 52, to provide a thin flat article, as shown in Fig. 3.

This one-piece filler may be elaborated to provide a one-piece container, illustrated in Figs. 12 to 18, which is formed from a strip of cardboard scored and folded in the manner heretofore described in connection with the filler, to provide inclined bottom members 51a and 52a, an upstanding central longitudinal partition portion 55a, and transverse partition members 65a pivotally secured at their lower corners to opposite sides of the bottom and arranged to swing upwardly therefrom. In this embodiment, however, the bottom members 51a and 52a are preferably of unequal inclination, but, if desired, they may be made of equal inclination as shown in connection with the filler illustrated in Fig. 1.

The parts of the one-piece container which correspond to those of the filler are designated by the same number with the addition of the letter "a". For example, the transverse partition members of the filler are designated by the numeral 65, and the transverse partition members of the container are designated by the numeral 65a.

The container is provided with a cover section 44a, and front and rear wall members 45a and 46a hinged to opposite edges of the cover along the score lines 47a and 48a. The cover and wall members are integral with and hingedly secured to the rear bottom member 51a along the score line 49a. The cover 44a, when the container is in erected position, extends across and rests on the tops of the longitudinal and transverse partition members, and the front and rear wall members 45a and 46a extend downwardly in engagement with the edges of the transverse members, as clearly illustrated in Fig. 15.

In containers of this class, it is desirable to provide means for locking the cover in closed position. To this end, the free edge of the front wall member 45a is provided with a plurality of prongs or hook-like members 85a which extend downwardly between the front group of tabs 71a and engage the inner face of the front inclined bottom member 51, see Fig. 15. Each of the members 85a is provided with a longitudinally extending slot 86a arranged along the free edge of the member 45a and adapted to receive a portion of the adjacent tab 71a, as shown in Fig. 12,

to lock the front wall member 45a thereto. The front row of tabs 71a thus not only provide a means for securing one end of the transverse members to the bottom and for locking the container in closed position, but also afford a support for the front wall 45a and thus cooperate with the transverse and longitudinal members to support the cover 44a, so as to prevent the latter from being pushed down and crushing the eggs.

When the usual type of filled containers are stored or shipped, they are arranged side by side so that the side walls of one container contact for substantially the full height thereof with the side walls of the container on either side. As these side walls are relatively weak, any blow or pressure thereon may break or crack the eggs within the container. To reduce the possibility of such breakage, the side walls of the above described container are preferably tapered as shown in Fig. 15, to slightly space the side walls of adjacent containers. By means of this arrangement, adjacent containers contact only along the upper corner line, as shown at 105, Fig. 15; and, as these corners are much stronger than the side walls and as they are spaced from the eggs within the compartment, the possibility of breakage is thereby materially reduced.

Empty containers of this class are usually shipped in the knocked down, or collapsed condition for obvious reasons. To collapse the container, the center partition portion 55a is disengaged from the transverse members 65a and moved downwardly so that the inclined bottom members 52a and the partition portion 55a lie in the same plane. The outer bottom members 51a are then folded on the score lines 50a, and, with the collapsed tongues 65a, overlie the portion 55a and the bottom members 52a. The back 46a and the cover 44a are then folded to overlie the tongues 65a and the front bottom member 51a, and the front 45a with its hook-like member 85a is then folded on the line 47a to overlie the bottom face of the adjacent bottom member 52a. The entire container may be thus folded or collapsed substantially into a plane, as clearly illustrated in Fig. 17.

Referring now to Fig. 19 there is shown another modification of the one-piece filler which provides what is known in the trade as the 3 x 4 arrangement, that is, three adjacent rows of cells each of which is divided into four separate article receiving compartments. This filler is formed in the manner above described to provide three rows of cells each having inclined cushioning bottom members 51b and 52b folded along the score line 50b, upstanding partition portions 55b intermediate the rows of cells, and transverse partition members 65b hingedly secured to opposite sides of the bottom and extending upwardly therefrom to divide the rows of cells into four separate article receiving compartments. The partition portions 55b preferably terminate slightly below the tops of the transverse members, as clearly shown in Fig. 19. The filler is arranged to be removably positioned with an outer box or body portion formed in the manner heretofore described. Corresponding parts of the filler and body parts are designated by the same numerals as in Figs. 1-11 with the addition of the letter "b". The filler, when removed from the body portion may be collapsed into a plane as shown in Figs. 21 and 22.

This 3 x 4 filler may be slightly elaborated to form a 3 x 4 container illustrated in Fig. 20. This

5 container is formed in the manner described in connection with the container illustrated in Figs. 12-18, except that in this embodiment the bottom members are of equal inclinations, as illustrated in the 3 x 4 filler shown in Fig. 19. The parts of the 3 x 4 container are differentiated from the corresponding parts of the 2 x 6 container by the addition of the letter "c".

10 While certain embodiments of the invention have been disclosed, it is to be understood that the inventive idea may be carried out in a number of ways. This application is therefore not to be limited to the precise details described, but is intended to cover all variations and modifications 15 thereof falling within the spirit of the invention or the scope of the appended claims.

I claim:

20 1. An article holder comprising a strip of sheet material formed to provide a bottom having an inclined cushioning portion with a substantially central longitudinal partition portion, and a transverse member secured to opposite sides of said bottom and having a plurality of tongues folded therefrom to extend upwardly above said 25 member to form with said center partition portion a plurality of article receiving compartments.

30 2. An article holder comprising a strip of sheet material formed to provide a bottom having an inclined cushioning portion with a substantially central longitudinal partition portion, and a transverse member secured to opposite sides of said bottom and formed to provide a plurality of tongues pivotally attached adjacent their lower 35 corners to said bottom and arranged to be swung upwardly above said pivotal attachment into spaced vertical planes to form with said center partition portion a plurality of article receiving compartments.

40 3. An article holder comprising a strip of sheet material folded to provide V-shaped bottom portions with a substantially central longitudinal partition portion, and a plurality of transverse partition members attached adjacent their lower edges to the outer sides of said bottom portions and arranged to swing upwardly relative to said 45 attachment to form with said center partition portion a plurality of article receiving compartments.

50 4. An article holder comprising a strip of sheet material having a part thereof folded upon itself to provide a vertical central partition portion terminating at its lower edges in inclined bottom portions, and a transverse member secured to opposite sides of said bottom portions and cut to 55 form a series of tongues swung upwardly above said member and into engagement with said partition portion to hold said bottom portions in inclined position.

60 5. An article holder comprising a strip of sheet material formed to provide a bottom having an inclined cushioning portion, a substantially central longitudinal partition portion, a cover, side members hingedly secured to said cover, and a transverse member secured to opposite sides of said bottom and slotted to provide a plurality of 65 tongues arranged to extend upwardly from said member to form in longitudinally spaced relation along said center partition portion a plurality of article receiving compartments.

70 6. An article holder comprising a strip of sheet material formed to provide a bottom having an inclined cushioning portion, a substantially central longitudinal partition portion, a cover, side members hingedly secured to opposite edges of said cover, one of said side members being hinged-

ly secured to one edge of said bottom to connect said cover and side members thereto, and a transverse member attached to opposite sides of said bottom and formed with a plurality of tongues arranged to be swung upwardly from said member to cooperate with said partition portion to maintain said cushioning portion in inclined position and to divide said holder into a plurality of article receiving compartments.

7. An article holder comprising a strip of sheet 10 material formed to provide V-shaped bottom portions with a substantially central longitudinal partition portion, a cover, side members hingedly secured to opposite edges of said cover, one of said side members being pivotally secured to one side 15 of said bottom portions to connect said side members and cover thereto, a transverse member secured to opposite sides of said bottoms and extending across the tops thereof, said transverse member being slit to form a plurality of tongues 20 hingedly secured at their lower corners to said bottom and arranged to swing upwardly into engagement with said partition portion and to cooperate therewith to hold said bottom portions in erected position and to divide said holder into a 25 plurality of article receiving compartments, and locking means arranged along the free edge of the other of said side members and adapted to engage a part of said transverse member to hold the cover and side members in closed position. 30

8. A container comprising, in combination, an enclosing body portion, and a removable collapsible filler positioned within said body portion, said filler being formed from a single piece of sheet material suitably scored and folded to provide a 35 bottom member having an inclined wall to afford a cushioning support for articles held therein and an upstanding center longitudinal partition portion, and a plurality of transverse partition members pivotally attached adjacent their lower 40 corners to said bottom member and arranged to be swung upwardly from said attachments into spaced vertical planes to form with said partition portion a plurality of article receiving compartments. 45

9. A container comprising, in combination, a collapsible body portion having a top, bottom, sides and ends, and a collapsible filler removably positioned within said body portion, said filler comprising a single piece of sheet material formed 50 to provide V-shaped bottom portions and a substantially central longitudinal partition portion, and a transverse member extending across the tops of and hingedly secured to opposite sides of said bottom portions, said transverse member 55 being formed to provide a plurality of tongues arranged to be swung upwardly from said member into engagement with said partition portion and cooperating therewith to maintain said bottom portions in erected position and to divide said 60 filler into a plurality of article receiving compartments.

10. A container comprising, in combination, an enclosing body having a bottom, ends, sides, and a cover having a closing flap, and a collapsible filler 65 removably positioned within said body portion, said filler being formed from a single strip of sheet material folded into substantially W-shape to provide V-shaped bottom portions and an upstanding center partition portion extending substantially to the top of said body portion, and a plurality of transverse partition members pivotally secured adjacent their lower edges to said bottom portions and extending upwardly therefrom into engagement with said partition portion to 70 75

hold said bottom portions in erected position and to divide said filler into a plurality of article receiving compartments, said filler, when removed from said body portion, affording a tray-like display carton adapted to resiliently support and cushion the articles positioned within said compartments.

11. An article holder comprising a strip of sheet material formed to provide a bottom having an inclined cushioning portion with a substantially central longitudinal partition portion, a transverse member secured to opposite sides of said bottom and formed to provide a plurality of tongues spaced longitudinally along said central partition portion and arranged to extend upwardly above said member to form with said central partition portion a plurality of article receiving compartments, and means for locking said partition portion and said tongues in interengaging relation to support said cushioning portion.

12. An article holder comprising a strip of sheet material formed to provide a bottom having an inclined cushioning portion, a substantially central longitudinal partition portion, a cover, side members hingedly secured to said cover, a transverse member secured to opposite sides of said bottom and slotted to provide a plurality of tongues arranged to extend upwardly from said member to form with said center partition portion a plurality of article receiving compartments spaced longitudinally along said central partition portion, and means for locking said partition portion and said tongues in interengaging relation to support said cushioning portion.

13. An article holder of sheet material comprising a bottom having an inclined cushioning portion, a substantially central longitudinal partition portion, and a transverse member secured to opposite sides of said bottom and formed to provide a plurality of tongues arranged to extend upwardly above said member to form in longitudinally spaced relation along said center partition portion a plurality of article receiving compartments.

14. An article holder of sheet material comprising a bottom formed to provide substantially V-shaped cushioning portions, a longitudinal partition portion between said V-shaped portions, and a transverse member secured to opposite sides

of said bottom and having a plurality of tongues folded therefrom to extend upwardly above said transverse member in engagement with said partition portion to support the same and said cushioning portions and form therewith a plurality of article receiving compartments.

15. An article holder of sheet material comprising transversely inclined article supporting and cushioning portions, a substantially central longitudinal partition portion, and a transverse member in the lower part of said holder having a plurality of longitudinally spaced tongues folded therefrom to extend upwardly above said member to form in longitudinally spaced relation along said central partition portion a plurality of article receiving compartments.

16. An article holder of sheet material comprising substantially V-shaped article supporting and cushioning portions, a longitudinal partition portion between said V-shaped portions, and a transverse member in the lower part of said holder formed to provide a plurality of longitudinally spaced tongues arranged to extend upwardly above said member to form with said partition portion a plurality of article receiving compartments.

17. An article holder made from a single strip of sheet material cut and folded to provide inclined article supporting and cushioning portions, a substantially central longitudinal partition portion, and a transverse member in the lower part of said holder having a plurality of longitudinally spaced tongues folded from said strip to extend upwardly above said member to form with said partition portion a plurality of article receiving compartments.

18. An article holder made from a single strip of sheet material cut and folded to form a substantially V-shaped portion providing substantially V-shaped article supporting and cushioning portions, an upstanding longitudinal partition portion, and a transverse member in the lower part of said holder having a plurality of longitudinally spaced tongues folded therefrom to extend upwardly above said member to form with said partition portion a plurality of article receiving compartments.
